GRATING FOR LIGHTING PANELS

Richard S. Hawes 3rd, Mosley Road, Creve Coeur, and
Frederick L. Hawes, 33 The Orchards, Olivette, Mo.

Filed Jan. 22, 1959, Ser. No. 54,273

Term of patent 14 years

(Cl. D48—16)

FIG. 1

FIG. 2

Figure 1 is a top plan view of a fragmentary section of a grating for lighting panels showing our new design; and Figure 2 is a sectional view taken along the line 2—2 of Figure 1.

We claim:

The ornamental design for a grating for lighting panels, as shown.
